J. W. EDMANDS.
RAILWAY SIGNAL FUSEE.
APPLICATION FILED MAY 6, 1914.

1,103,277.

Patented July 14, 1914.

FIG. 1. FIG. 2. FIG. 3. FIG. 4. FIG. 5.

UNITED STATES PATENT OFFICE.

JOHN W. EDMANDS, OF NEWTON CENTER, MASSACHUSETTS, ASSIGNOR TO CENTRAL RAILWAY SIGNAL COMPANY, OF PITTSBURGH, PENNSYLVANIA, A CORPORATION OF NEW JERSEY.

RAILWAY SIGNAL-FUSEE.

1,103,277

Specification of Letters Patent.

Patented July 14, 1914.

Application filed May 5, 1914. Serial No. 836,581.

To all whom it may concern:

Be it known that I, JOHN W. EDMANDS, a citizen of the United States, residing at Newton Center, in the county of Middlesex 5 and State of Massachusetts, have invented certain new and useful Improvements in Railway Signal-Fusees, of which the following is a specification, reference being had therein to the accompanying drawing.

10 This invention relates to improvements in railway signal fusees.

The present invention pertains to an improvement in the manner of connecting to one end of the tube a spike by which the 15 fusee may be supported in an upright position by driving the spike either in the ground, road-bed or railroad tie in a manner well known to those acquainted with the use of railway signal fusees.

20 Heretofore spikes have been attached to or made a part of a plug, sometimes wood and sometimes metal, and this plug is made of a size to fit the end of the fusee and is glued therein. Where the plug or means 25 of attaching the spike is within the open end of the fusee tube, it is liable to become detached, and the primary object of my present invention is to attach the spike to a crimped end closure which is a part of 30 the tube itself so that it is not possible for the spike to become lost or detached from the tube, nor is it possible for the end of the tube to become open, and the compound 35 therein permitted to sift out of the tube in transportation, which latter would be the case where a plug is inserted in the open end of the tube and becomes detached therefrom.

40 In the accompanying drawings:—Figure 1 is a perspective view of the spike end of a fusee tube with one form of my improvement applied thereto. Fig. 2 is a sectional view of Fig. 1. Figs. 3, 4, 5, 6, 7, 8, 9, 45 and 10 each show modified forms or constructions which embody my present improvement. Fig. 11 is an enlarged top view of the clamping washer shown in Figs. 1 and 2.

50 In carrying out my improvement, I provide the paper or fiber fusee tube 1 with a crimped closed end 2 which closed end is an integral part of the tube itself.

55 Referring now particularly to the form shown in Figs. 1 and 2, the nail or spike 3 is provided with a suitably enlarged head 4.

The stem of the spike passes through the crimped closure 2 of the tube so that the head is on the inside of the tube. The clamping washer 5 is then passed over the stem of the spike and forced downward 60 against the outer side of the closure 2 thus clamping the closure firmly between the head 4 and the washer 5 and firmly clamping the spike to the closed end of the fusee tube. The form of washer shown in Figs. 65 1 and 2 and 11 is slightly dished outwardly as shown and has its opening 5^a, formed with lateral recesses 5^b, which form between the recesses prongs or arms 5^c. These arms are forced in frictional engagement with 70 the stem of the spike either by pressing the dished washer inward at its center which will cause the arms 5^c to grip the stem of the spike 3, or the ends of the arms may be swaged so as to grip the step of the 75 spike. Where it is desired to weight the spike end of the fusee, a separate cement or iron plug 6 may be placed within the tube and between the head 4 of the spike and the burning composition 7, and this 80 weight may be used in connection with any of the forms herein shown. When it is not desired to weight the spike end of the fusee, the plug 6 will be omitted and then the burning composition 7 is packed directly 85 against and in contact with the head of the spike.

In Fig. 3 the construction is slightly modified in that the head 4 of the spike 3 is slightly cup-shaped and the washer 8 90 forces the closure 2 down into this cup-shaped head as shown, thus making a bent portion of the closure, making a sort of a lock. In this instance, the washer may have an opening without any lateral recesses 95 and the washer may be made to tightly fit the stem of the spike.

Fig. 4 shows a construction similar to Fig. 3, and in which a washer 8, like that shown in Fig. 3, is used but in this instance, the outer surface of the stem of the spike is pinched by a suitable implement to form ears or shoulders 9 against the outer surface of the washer 8, and these ears or shoulders serve to hold and lock the washer 105 in position.

Fig. 5 shows a construction like that shown in Fig. 4, and differs therefrom only in having the stem of the spike provided with a tapered portion 3^a, and the washer 110

is forced down on this tapered portion so that the washer is wedged and held into position.

Fig. 6 differs from Figs. 1 and 2 in that the head of the spike 4^a, is made cone-shaped and the closure 2^a correspondingly cone-shaped, and the washer 10 differs only from the washer 5 in that it is made cone or dome-shaped to correspond with the cone or dome shaped closure 2^a. This construction is used when it is desired to have the closure of the fusee of a dome shape.

Fig. 7 shows a modification in that the stem of the spike is provided with an integral flange 11 that fits against the outer side of the closure 2, and a washer 12 is clamped to the inner side of the closure 2 by swaging the projection or end 13 of the spike, which receives the washer thus clamping the closure 2 between the flange 11 and the washer 12.

Fig. 8 shows a modification in that the washer 8 is clamped to position by turning a portion of the spike outward against the washer as shown at 14 and thus serves to clamp the closure 2 between the washer 8 and the head 4 of the spike.

Fig. 9 is a modification of Fig. 3 in that the washer 8 is omitted and the stem of the spike is turned outward into a flange 15 which clamps the closure 2 between the head 4 of the spike, and the turned flange 15 of the stem of the spike.

Fig. 10 is a modification in that the closure 2 is provided with a metallic eyelet 16, and the stem of the spike 3 provided with a flange 17 near its inner end, and the inner end projected through the eyelet and swaged or expanded as shown at 18 to clamp the closure 2 between the flange 17 and the expanded end 18, the eyelet serving to furnish a metallic surface against which the flange and expanded end are clamped, the eyelet serving, of course, to strengthen the closure 2.

From the foregoing, it will be observed that in all the forms here shown the spike is secured to the fusee by clamping it to a crimped closure of the tube which closure is formed as an integral part of the tube.

I wish it understood that while this invention is particularly intended for use in railway time burning fuses, it is capable of use with any tube having a crimped end closure which contains a burning compound whether that compound be of the character used in railway time burning signal fuses or in fireworks, whenever it is desired to have the tube supported in an upright position while the composition therein is burning, and in fact, it may be applied to Roman candles so that they can be supported in an upright position by driving the spike into

the lawn, or into a board placed for that purpose. In other words, the invention is adapted for use in fireworks or torches which have an end closure.

Having thus described my invention what I claim and desire to secure by Letters Patent is:

1. A device of the character described, comprising a tube, the tube having an end closure, and a spike carrying clamping members engaging the inner and outer sides of the closure to clamp the spike thereto.

2. A device of the character described, comprising a fiber tube having an inwardly crimped end closure, a spike having laterally extending members engaging the inner and outer sides of the closure and clamping the spike thereto.

3. A device of the character described, comprising a tube having an end closure, a spike having a head at the inner side of the closure, the stem of the spike passing through the closure, and a washer applied to the stem of the spike and engaging the outer side of the closure to clamp the spike thereto.

4. A device of the character described, comprising a tube having an end closure, a spike having an integral laterally extending head or flange, and a washer, the two laterally named elements respectively engaging the inner and outer sides of the closure and clamping the spike thereto.

5. A device of the character described, comprising a fiber tube having an end closure, a spike having a cup-shaped head engaging one side of the closure, and a washer applied to the spike and engaging the other side of the closure, the washer held in position by engagement with the stem of the spike.

6. A device of the character described, comprising a tube having an end closure, a spike having a head engaging one side of the closure, a washer applied to the stem of the spike and engaging the other side of the closure, the spike stem swaged to lock the washer to the stem of the spike.

7. A device of the character described, comprising a tube having an end closure, a spike having a head engaging the inner side of the closure, a washer applied to the stem of the spike and against the outer side of the closure, the stem of the spike having a laterally extending shoulder engaging the outer side of the washer for locking the washer in position.

In testimony whereof I hereunto affix my signature in the presence of two witnesses.

JOHN W. EDMANDS.
